UNITED STATES PATENT OFFICE.

BENJAMIN F. LIVELY, OF LENOIR CITY, TENNESSEE.

DOOR-OPERATING MECHANISM.

1,108,769.

Specification of Letters Patent. Patented Aug. 25, 1914.

Application filed April 10, 1914. Serial No. 820,933.

To all whom it may concern:

Be it known that I, BENJAMIN F. LIVELY, a citizen of the United States, residing at Lenoir City, in the county of Loudon and State of Tennessee, have invented new and useful Improvements in Door-Operating Mechanism, of which the following is a specification.

This invention relates to improvements in door operating mechanism and has particular application to a mechanism for operating the doors of hopper cars.

In carrying out the present invention, it is my purpose to provide an operating mechanism for the doors or gates of hopper cars whereby such doors may be swung to open and closed positions and whereby the doors will be securely and positively locked in closed position to prevent the accidental opening thereof.

It is also my purpose to provide a mechanism of the class described whereby the doors or gates of hopper cars may be swung to open and closed positions and whereby such doors may be held in any desired position during the opening thereof so that the discharge of the material from the hopper or chute of the car may be regulated or controlled.

Furthermore, I aim to provide a mechanism of the type set forth which will embrace the desired features of simplicity, efficiency and durability, which may be installed and maintained at a minimum expense and which will embody few parts and these so correlated and arranged as to reduce the possibility of derangement to a minimum.

With the above and other objects in view, the invention consists in the construction, combination and arrangement of parts hereinafter set forth in and falling within the scope of the claims.

In the accompanying drawings; Figure 1 is a fragmentary longitudinal sectional view through a hopper car equipped with a door operating mechanism constructed in accordance with the present invention. Fig. 2 is a transverse sectional view thereof. Fig. 3 is a diagrammatic view of the operating mechanism showing the same in closed position. Fig. 4 is a top plan view thereof. Fig. 5 is a sectional view through a portion of the operating mechanism.

Referring now to the drawings in detail, 1, 1 designate the center sills of the car

structure, 2 the side girders and 3 the inclined floor of the hopper chutes. Closing the discharge end of each chute is a gate or door 4 pivoted at its upper end for 30 swinging movement, as is well known.

Depending from the center sills 1 are transversely disposed alining bearings 5 and journaled within the bearings and capable of rotation therein is an actuating shaft 6 extending transversely of the car and having the opposite extremities thereof journaled in horizontally alining bearings disposed adjacent to the opposite sides of the car body and secured to the latter in some suitable manner. Fast upon the actuating shaft 6 and projecting outwardly therefrom is an arm 7 having the outer end thereof formed to provide a forked pivot knuckle 8 having the opposite limbs thereof formed 75 with alining slots 9. Mounted within the slots 9 and capable of sliding movement therein is a pin 10 carried by a pivot knuckle 11 disposed between the limbs of the forked knuckle 8 and connected with one 80 end of a link 12. The opposite end of the link 12 is formed with a pivot knuckle 13 lying between the limbs of a forked knuckle 14 upon one end of an actuating rod 15. The end of the rod 15 equipped with the 85 forked knuckle 14 is curved as at 16 to fit around the shaft 6, while the opposite end of such rod is connected through suitable means 17 with the lower end of the dumping door or gate. Connected with the inner 90 end of the arm 7 and disposed at right angles thereto is a lug 18.

In practice; when the door or gate is open the arm 7 and link 12 are coextensive with each other and disposed upon one side of the 95 actuating shaft 6, while the lug 18 extends downwardly. On the other hand, when the shaft is rotated to swing the gate to closed position the arm 7 moves through an arc to the opposite side of the actuating shaft and 100 through the medium of the link 12 exerts a pull upon the rod 15 to close the gate. In the initial movement of the arm under the action of the shaft the pin 10 rides from one end of the slots 9 in the forked knuckle 105 8 to the opposite ends of such slots and the lug 18 enters the space between the limbs of the forked knuckle 14 behind the knuckle 13 on the link 12, while in the continued movement of the arm under the action of 110 the shaft the lug 18 engages the adjacent knuckle on the link and pulls the actuating

rod 15 to closed position independently of the movement of the arm 7, the lug imparting movement to the link to slide the latter relatively to the arm so that the pin 10 rides 5 within the slots 9 to the opposite ends of the latter as clearly illustrated in Fig. 3. In the movement of the actuating rod under the action of the lug 18 the curved portion 10 of the rod fits about the actuating shaft thereby throwing the pivotal connection between the link and the actuating rod upon the side of the actuating shaft opposite from the gate and below the center line of such shaft. Thus, the parts are locked against 15 accidental movement and the gate securely held in closed position.

In order to rotate the actuating shaft, I employ, in the present instance, a worm 19 journalized in bearings carried by a bracket 20 suitably fastened to the lower wall of the chute. Fixed to the shaft 6 is a worm wheel 21 meshing with the worm 19 and inclosed by a casing 22 carried by the bracket 20. Fast to the worm 19 is a crank handle 23 by means of which the worm may be rotated to impart motion through the worm wheel 21 to the actuating shaft 6. It will be seen that when the worm is rotated under the action of the crank handle 23 the worm 30 wheel will be revolved with the effect to rotate the actuating shaft 6 so that the operating and locking mechanism of the door will be actuated as previously described, while the worm wheel being fast upon the shaft 35 and meshing with the worm will act to hold the shaft in any desired position thereby enabling the gate or door to be opened to any extent.

While I have herein shown and described 40 one preferred form of my invention by way of illustration, I wish it to be understood that I do not limit or confine myself to the precise details of construction herein described and delineated, as modification and 45 variation may be made within the scope of the claims without departing from the spirit of the invention.

I claim:

1. In a door operating mechanism for 50 hopper cars, an actuating shaft capable of rotation, an arm fast to said shaft and extending outwardly therefrom, a link con-

nected with the outer end of said arm and lying upon said arm when the latter is at one side of said shaft and coextensive with 55 the arm when the latter is at the opposite side of the shaft, a door actuating rod having one end pivotally connected to said link and said end curved to fit around said shaft in the closed position of the door whereby 60 the pivotal connection between said link and rod will be disposed upon the side of the center line of said shaft opposite the door to lock the door against opening movement, and a lug extending outwardly from said 65 shaft at an angle to said arm and adapted to engage the arm end of said link in the closing of the door to actuate said rod independently of said arm.

2. In a door operating mechanism for 70 hopper cars, an actuating shaft capable of rotation, an arm fast to said shaft and extending outwardly therefrom and having the outer end thereof formed to provide a forked pivot knuckle, a link having one end 75 thereof equipped with a pivot knuckle lying between the limbs of said first knuckle, a pin and slot connection between said knuckles, a pivot knuckle on the opposite end of said link, said link lying upon said 80 arm when the latter is at one side of said shaft and coextensive with said arm when the latter is at the opposite side of the shaft, a door actuating rod having one end thereof curved and formed with a forked pivot 85 knuckle receiving the last-mentioned pivot knuckle, the curved end of said rod fitting around said shaft in the closed position of the door whereby the pivotal connection between said link and rod will be disposed 90 upon the side of the center line of said shaft opposite the door to lock the door against opening movement, and a lug extending outwardly from said shaft at an angle to said 95 arm and adapted to enter the forked end of said rod behind the link pivot knuckle therein to actuate said rod independently of the arm.

In testimony whereof I affix my signature in presence of two witnesses.

BENJAMIN F. LIVELY.
